CLAIM

The ornamental design for a shoe cover, as shown and described.

DESCRIPTION

FIG. 1 is a front, right and top perspective view of a shoe cover, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of area “9” in FIG. 2.

The even dash broken lines depict portions of the shoe cover that form no part of the claimed design. The dot-dash broken lines depict the boundaries of the enlargements and form no part of the claimed design.

1 Claim, 9 Drawing Sheets
